UNITED STATES PATENT OFFICE.

AZEL CLARENCE HOUGH, OF SOUTH BUTLER, NEW YORK.

DESIGN FOR A DESK-RAILING.

SPECIFICATION forming part of Design No. 22,024, dated November 29, 1892.

Application filed October 22, 1892. Serial No. 449,705. Term of patent 7 years.

To all whom it may concern:

Be it known that I, AZEL CLARENCE HOUGH, a citizen of the United States, residing at South Butler, in the county of Wayne and State of New York, have invented certain new and useful Improvements in Designs for Desk-Railings, &c.; and I do declare the following to be a full, clear, and exact description of the invention, such as will enable others skilled in the art to which it appertains to make and use the same, reference being had to the accompanying drawing, and to the letters of reference marked thereon, which form a part of this specification.

15 My invention relates to designs; and it has for its object the enhancing of the appearance of the desks or casings of recorders, cash-registers, and the like by an attractive rail and shelf; and to these ends the invention consists in the design for the rail at the front, the bracket and side rail supporting the latter, and the shelf, substantially as hereinafter specified and illustrated in the accompanying drawing, in which I have shown 20 a perspective view of a portion of a cash-register desk embodying my design. The leading or characteristic feature of my design is the rail rising in two panels, one on either side of an upright opening, and having at 25 the outer extremities of each rail a return-bracket in the form of a quadrant, the floor of the upright opening comprising a quadrangular platform having a slightly-raised border.

30 Reference now being had to the details of the drawing by letter, A A designate two

vertical posts or rods placed at opposite sides of the desk-top near its front edge, and B B two other posts arranged in line with the others. The posts B B are approximately 40 twice as high as the posts A and are connected near their upper ends by a horizontal rod or bar b, whose ends are extended for a short distance beyond the posts. Two horizontal parallel rods or bars a a extend between each 45 post A and the adjacent post B, said rods being connected by vertical rods or bars a'. Upon the upper end of each post is provided a ball or sphere c, and balls c' are also placed upon the vertical rods a'. Upon each side of 50 the desk is a bracket forming a side rail, said bracket being in the form of a quadrant whose upper end is in line with the upper rod a, a straight horizontal bar C' in line with the lower rod a, and a diagonally-extending rod C², 55 corresponding with the vertical rods a'. Attached to the desk-top and projecting from the edge thereof outward is a shelf D, the plan of which is quadrangular with the corners removed. The shelf is provided with a 60 depressed panel, which is formed in its upper face by a raised border or margin.

What I claim as new is—

The design for a railing, substantially as shown and described. 65

In testimony whereof I affix my signature in presence of two witnesses.

AZEL CLARENCE HOUGH.
